CLAIM

The ornamental design for the snowboard binding strap assist mechanism, as shown and described.

DESCRIPTION

FIG. 1 is a perspective view of a snowboard showing a pair of binding strap assist mechanisms in accordance with the present invention.

FIG. 2 is an enlarged perspective view binding strap assist mechanisms of FIG. 1 on an open binding.

FIG. 3 is an enlarged perspective view binding strap assist mechanisms of FIG. 1 on a closed binding; and,
FIG. 4 is a side view of the binding strap assist mechanisms of FIG. 2.

1 Claim, 4 Drawing Sheets

FIG. 3

FIG. 4
